United States Patent Office

Des. 181,879
Patented Jan. 7, 1958

181,879

INDEX DIVIDER PACKAGE

Frederick H. Rice, Van Nuys, Calif.

Application September 8, 1954, Serial No. 32,193

Term of patent 14 years

(Cl. D58—2)

I claim:

The ornamental design for an index divider package, as shown.
